UNITED STATES PATENT OFFICE.

CLARENCE A. BERKINS, OF MINNEAPOLIS, MINNESOTA.

GAS GENERATOR AND BURNER.

Application filed April 13, 1921. Serial No. 462,181.

To all whom it may concern:

Be it known that I, CLARENCE A. BERKINS, a citizen of the United States, residing at Minneapolis, in the county of Hennepin and State of Minnesota, have invented certain new and useful Improvements in Gas Generators and Burners; and I do hereby declare the following to be a full, clear, and exact description of the invention, such as 10 will enable others skilled in the art to which it appertains to make and use the same.

My present invention provides an extremely simple and highly efficient gas generator and burner especially adapted for 15 use in ranges and cooking stoves but capable of more general use. It is of the type especially adapted for use in vaporizing and burning liquid hydro-carbon fuels, such as gasoline and kerosene.

Generally stated, the invention consists 20 of the novel devices and combinations of devices hereinafter described and defined in the claims.

This burner is adapted to be placed in the 25 fire pot of a range or similar stove directly upon the grate thereof, and, hence, is readily applicable to ranges and cooking stoves such as found on the market and already in use. It comprises a so-called air box or chamber formed with an open bottom adapted 30 to be placed directly on the grates and provided on top with a deck formed with one or more, preferably two, upstanding air nozzles. Overlying the air nozzles are reflectors of novel arrangement. The fluid 35 fuel supply pipes are brought in through the bottom of the air box or chamber and are connected to generating tubes that extend around or approximately around the 40 air nozzles and are terminated in nozzle pipes that extend through the respective air nozzles and are arranged to discharge within the latter.

The preferred form of the burner is illustrated 45 in the accompanying drawings, wherein like characters indicate like parts throughout the several views.

Referring to the drawings:

Fig. 1 is a side elevation of a range 50 equipped with the improved burner, some parts of the side wall of the range being broken away;

Fig. 2 is a transverse vertical section

taken approximately on the irregular line 2-2 of Fig. 1;

Fig. 3 is a plan view of the generating burner removed from the range;

Fig. 4 is a vertical section taken approximately on the irregular line 4-4 of Fig. 3; and

Fig. 5 is a transverse section on the line 5-5 of Fig. 4.

Of the parts of the range, it is only desirable, for the purposes of this case, to particularly note the main or outer shell 6, the oven 7, the grate 8 and the frame chamber 9 that extends over down one side and under the oven and thence to the smoke pipe in the customary way.

The so-called air box or chamber 10, of 70 the generator and burner, as stated, is open at its bottom and placed directly on the grate 8, within the fire pot of the range. The top of this air box is in the form of a deck 11 provided near the ends of the box 75 10 with upstanding air nozzles 12 that are open to said air box preferably through a plurality of air passages 13 in said deck.

Spaced above each air nozzle 12 is a deflector preferably in the form of a heavy 80 disk-like head 14 formed on the extremities of arms 15 that project in opposite directions from a supporting stem 16. This stem 16 is preferably made angular and tapered at its lower end and detachably seated into 85 the corresponding form seat of a lug-like socket 17 cast integral with the flange of the deck 11. For an important purpose, which will presently appear, the under-surfaces of the deflector 14 and the upper edge 90 surfaces of the nozzles 12 are inclined in a direction away from the oven 7.

The fluid hydro-carbon fuel is delivered to the burner through small supply pipes 18, which, as shown, are tapped into expanded 95 couplings 19 and, at their upper ends, are provided with bushings 20 that contract the supply passages at such points. The generating tubes 21 are of approximately U-shaped form and extend in a horizontal direction 100 around the respective nozzles 12 but are spaced therefrom. At their receiving ends, the generating tubes 21 are connected by elbows 22 to short pipe sections 23 that extend downward through the deck 11 into 105 the air box 10 and have threaded engage-

ment with the couplings 19. Nuts 24, on the pipes 23, bear against the deck 11 and clamp the couplings 19 against the same, thereby firmly supporting the generating tubes.

The generating tubes are provided with nozzle extensions 25 that are extended freely through large diametric openings in the sides of the air nozzles 12 and, at the center of said nozzles, are provided with small upwardly opening discharge passages 26 through which the generated vapor or gas will be discharged directly upward. The outer ends of the nozzle extensions 25 are closed by caps 27.

By reference to Fig. 3, it will be noted that the engineering tubes 21-25 extend through approximately three hundred and sixty degrees around the respective nozzles and from thence extend in opposite directions outward diametrically through the respective nozzles. This positions the generating tubes where they will be subjected to heat from the flames of the burner throughout the complete circle or three hundred and sixty degrees and, consequently, gives a maximum vapor generation.

The supply pipes 18 are preferably brought into the ash pit chamber of the stove through the damper-equipped draft opening 28 and are connected through valves 29 to the depending delivery tube 30 of the fuel supply tank 31. Preferably, a layer of ashes y will be placed on the grate 8 around the base of the air box 10, so that the only draft through the grate will be upward through said box.

In starting the generating action, kerosene or gasoline can be poured onto the ashes 40 and ignited, and after the generating tubes are hot enough to produce generation of gas or vapor, the supply of the liquid fuel will be turned on and, thereafter, the generation will be automatic.

45 The flames from the nozzles 12 will strike directly against the oblique under-surfaces of the deflector heads 14 and will be spread somewhat in all directions around said heads

but there will be a marked general deflection of the flames over the top of the oven, as indicated by arrows on Figs. 2 and 5. This is important because it prevents too intense heat on the front griddles and causes more even distribution along the under-surface of the entire top of the stove or range. In shipment, the T-shaped structure, which includes the deflecting heads 14, may be lifted out of position and placed where it will not interfere with close packing of the device and where said removal device is not liable to be broken. Preferably, said deflecting device is made in the form of an integral gray iron casting, which is well adapted to withstand heat but quite easily broken when roughly handled.

What I claim is:

1. A generator and burner of the kind described comprising an air box having an open bottom and provided at its top with an upstanding nozzle and a deflector spaced from but overlying said nozzle, a fluid fuel supply pipe extended through said box to the top thereof, a generating tube connected to said fuel supply pipe and extending around said nozzle through approximately three hundred and sixty degrees and from thence passing diametrically through said nozzle and provided within said nozzle with a fuel discharge port.

2. A duplex generator and burner of the kind described comprising an air box having an open bottom and provided in its top with two upstanding air nozzles and above said nozzles with deflectors, fluid fuel supply pipes extended upward through the central portion of the top of said box, generating tubes connected to the respective fuel supply pipes and extending around the respective nozzles through approximately three hundred and sixty degrees and from thence extended in opposite directions diametrically outward through the respective nozzles and provided within said nozzles with fuel discharge ports.

In testimony whereof I affix my signature.

CLARENCE A. BERKINS.
